ABSTRACT: An electrical circuit is provided for powering an alternating current motor of a conventional feed dispensing device or other devices with the circuit being operable for a selected short period of time under the control of an automotive type electrically wound clock having a first circular array of pin contacts engageable by a ribbon contact on the hour hand and a second circular array of pin contacts engageable by ribbon contacts on the minute hand with power to the alternating current motor being provided by an inverter operated at only those times when the hour hand and the minute hand pin contacts are simultaneously engaged so as to close the circuit to the inverter.

AUTOMATIC CONTROL MEANS FOR FEEDER

BACKGROUND OF THE INVENTION

BACKGROUND OF THE INVENTION

This invention is in the field of control devices and is specifically directed to the combination of a timer control system and a wildlife feeder or the like for operating the feeder for a given time period at a desired time or times of day. Even more specifically, the invention is directed to a battery operated system for providing alternating current from a battery to an alternating current drive motor for a desired time and for a desired time period or periods.

The provision of power means and control circuitry for operating wildlife feeders located in places accessible to conventional alternating current is a relatively simple matter since there are numerous alternating current driven timers available for providing alternating current at desired times and for desired time intervals. However, wildlife feeders, by their very nature, must frequently be located far in the field many miles from any source of conventional alternating current. Consequently, it is impossible to employ conventional alternating current timers in such locations. Additionally, it is desirable that all wildlife feeders be interchangeable between remote locations in which alternating current is not available and those locations in which alternating current is available in order to enable interchange of the various feeders as the feed requirements vary.

Prior to this invention, no satisfactory means have been proposed for automatically enabling the operation of wildlife feeders in locations not having alternating current. Moreover, prior to this invention, no known wildlife feeders were capable of being used in remote locations not having alternating current and also being capable of being used in those locations having alternating current.

The subject invention provides a means whereby remotely located wildlife feeders can be operated automatically at a set time (or times) each day and for a set time period or periods of operational duration. Moreover, the instant invention enables the usage of the same type feeder (i.e., an alternating current driven feeder) in both remote locations not having alternating current and those locations having such current. For these reasons, the subject invention provides a solution to the problem of enabling the automatic dispensing of feed in remote locations by the employment of conventional feeders operable at either such remote locations or at less-remote locations having alternating current.

SUMMARY OF THE INVENTION

Therefore, it is the primary object of this invention to provide new and improved control means for operating wildlfie feeders or the like in remote locations not having alternating current.

Obtainment of the object of this invention is enabled through the provision of control means in which a battery is provided for operating an intermittently wound automotive-type clock. The clock member is provided with a first circular array of tubular sleeve-type socket members which are threaded to receive a threaded rodlike pin contact member.

The pin contact member can be inserted in any one of the tubular socket members and a ribbon contact on the end of the hour hand will engage any contact member in the first circular array as the hand moves into alignment with the pin. Additionally, a second circular array of threaded tubular socket members is provided outwardly of the first circular array with the socket members of the second array being identical to those of the first array. A ribbon contact on the end of the minute hand is similarly positioned for engaging any contact member mounted in any of the socket members of the second array. The length of the ribbon contact on the minute hand determines the duration of engagement of the ribbon contact with the particular rod like contact. A pair of electrically operable solenoids are provided with each solenoid having a normally open switch. The normally open switches of the first

and second solenoids are connected in series to one pole of a conventional inverter. The other pole of the inverter is connected to the battery and electrical potential is provided to the handle of the clock from a conductor connected to the battery. The first solenoid coil is connected to the first circular array of socket members and the second solenoid coil is connected to the second solenoid coil is connected to the second circular array of socket members. Consequently, it is necessary for both the hour hand and the minute hand to be contacting one of the pin contact members of the first and second circular arrays respectively in order for both of the solenoid switch elements to be simultaneously closed to operate the inverter. The power output from the inverter is in the form of alternating current which drives an alternating current motor for operating the feeder. The duration of the time period during which the feeder is operated depends upon the length of the ribbon contact member on the minute hand and can be varied by merely substituting a new minute hand having a different length ribbon contact. The duration of the feed period can be varied downwardly to less than one minute if desired.

DESCRIPTION OF THE DRAWINGS.

FIG. 1 is a schematic of the electrical circuitry employed in the preferred embodiment of the invention.

FIG. 2 is a front elevational view of the clock face and casing employed in the preferred embodiment; and

DESCRIPTION OF THE PREFERRED EMBODIMENT

Turning first to FIG. 1, it should be noted that the preferred embodiment is in the form of electrical circuit means generally designated 20 which is provided for operating a conventional wildlife feeder 22 having an alternating current drive motor (not shown) in a motor housing 24. The actual feeder employed is immaterial insofar as this invention is concerned and practically any conventional feeder operated by an alternating current motor could be employed.

40 an alternating current motor could be employed. The control circuitry is contained within a conventional housing (not shown) for protection against the weather and other environmental hazards and includes a main 12-volt battery means 26 which provides the required electrical power. 45 Battery 26 is provided with a first, or negative, terminal 28 and a second, or positive, terminal 30. First and second main power lines 32 and 34 extend from the first and second terminals 28 and 30 and are connected to a winding motor 36 of a substantially conventional automobile-type clock drive of 50 the type in which the winding motor 36 is intermittently operated for winding the clock. However, the clock device has been modified through variation of the drive ratio to the hour hand to the extent that the hour hand makes only one revolution for each 24 hours. Therefore, the clock is a 24-hour 55 clock. Such clocks are conventional and the details of construction of the clock form no part of this invention. The works of clock 38 are mounted within an enclosure 40 which protects the works of the clock from the environmental dangers of moisture, dust and the like. The face of the clock is in the form of a plastic plate 42 provided with a circular hole

the form of a plastic plate 42 provided with numerical designators 44 indicative of the hours of the day. A removable cover 45 fits over the face of the clock. Additionally, the clock includes an hour hand 46 and a minute hand 48 respectively mounted on coaxial drive shafts 47 and 49 extending forwardly of plate 42. A flexible ribbon-like contact 50 is provided to extend from the end of the hour hand and a similar flexible ribbonlike contact 52 extends from the end of the minute hand 48. Both the hour hand and the minute hand can be removed if desired in order to enable replacement with hands having ribbon-like contacts of different length for a purpose to be discussed hereinafter.

A first circular array 54 of fixed individual socket members 56 is provided in plastic plate 42 as shown in FIGS. 1 and 3. Each individual socket member comprises a hollow cylindrical

threaded sleeve-like member having threads on its interior so that an hour hand pin contact member 58 can be threaded into any one of the sockets 56 as desired. Contacts 58 are in the form of a solid electrically conducting rod or pin as shown in FIG. 3. Each of the individual sockets 56 are connected by a circular electrical conductor 60.

Similarly, a second circular array 62 of sockets is provided outwardly of the first circular array 54 and is formed of a plurality of socket members 64 which are of a larger diameter than the socket members 56. Each of the socket members 64 of the second circular array is connected electrically to the others by means of a circular conductor 66. A pin contact member 65 having threads on one end is receivable within any one of the socket members 64 in the same manner as pin contacts 58 are received in sockets 56. However, it should be noted that the contacts 65 are of greater length and diameter than the contacts 58 as shown in FIG. 3 in order that contacts 65 will be engaged by the ribbon like contact 52 on the end of the minute hand 48. Similarly, it should be noted that the contacts 58 are engageable by the ribbon like contact 50 on the end of the hour hand 46 but are too short to be engaged by the minute hand 48.

A conductor 68 conducts the minute hand and the hour hand to the second main power line 34. The circular conductor 60 of the first array of sockets is connected by a conductor 70 to one coil terminal of a first relay solenoid 72 and the other coil terminal of the first relay solenoid 72 is connected by a conductor 74 to the first main power line 32. The first solenoid 72 includes a normally open switch 76 which is closed upon actuation of the solenoid coil of solenoid 72.

In like manner, the conductor 66 of the outer array 62 of sockets is connected by a conductor 78 extending to one terminal of the coil of a second relay solenoid 80. The second relay solenoid 80 is provided with a switch contact 82 that is normally open in the same manner as switch contact 76. The other terminal of the coil of second relay solenoid 80 is connected by a conductor 84 to the first main power line 32.

Switch contacts 76 and 82 are connected in series by conductors 86, 88 and 90 respectively extending from the second main power line 34 to one terminal of a conventional inverter which, when provided with direct current, provides an alternating current output to power output lines 100 connected to the alternating current motor housing 24. The other input terminal of the inverter 92 is connected by a conductor 104 to the first main power line 32.

In operation, the user inserts an hour hand pin contact 58 in the particular socket member of the first circular array of socket members which correspond to the hour in which it is desired that the feeding operation take place. For example, FIG. 2 illustrates a pin 58 positioned in the socket corresponding to 3 a.m. on the 24-hour scale.

Similarly, a minute hand pin contact 65 is inserted in the socket in the second circular array of sockets corresponding to the initial minute of the feeding period to be provided.

For example, FIG. 2 illustrates a minute hand pin contact 65 in the position corresponding to 40 minutes past the hour. Therefore, the minute hand would engage the pin contact 65 at approximately 40 minutes past the hour and will remain in contact with the pin 65 for a time period depending upon the length of the ribbon contact 52. The shorter the contact—the shorter the time period.

If one assumes that the pin 58 is in the position shown in FIG. 2 and the pin 65 is similarly in the position illustrated in FIG. 2, the hour hand would initially engage the pin 58 at approximately 3 o'clock at which time the minute hand would be in substantially the 12 o'clock position. The hour hand would remain in contact with pin 64 for almost 1 hour due to the flexibility and length of ribbon contact 50. The engagement of the hour hand with the pin contact 58 will serve to complete a circuit from the battery through the second main power line 34, conductor 68, hour hand 46, ribbon contact 50, pin contact 58, circular conductor 60, conductor 70, first solenoid coil 72, conductor 74 and first main power line 32 to the other

terminal 28 of battery 26. Consequently, solenoid 72 will be activated to close contact switch 76. However, a circuit could not be completed to the inverter 92 at this time since the second solenoid 80 cannot be activated until the minute hand engages the pin contact 65 (some 40 minutes hence). However, upon the passage of approximately 40 minutes, the minute hand ribbon contact 52 engages pin 65 to actuate the second solenoid coil 80 and close switch contact 82 to complete the circuit through conductor 86, conductor 88, switch contact 76 (previously closed when the hour hand engaged pin 58) and conductor 90 to the inverter 92. Consequently, alternating current is provided from inverter 92 to line 100 for operating the feeder 22. However, as soon as the minute hand moves past the 40-minute position to an extent sufficient for the ribbon contact 52 to clear the pin contact 65, the second solenoid 80 will be deactivated to deactivate the circuit to the inverter. The circuit will not again be reactivated for 24 hours since it will be that length of time before the hour hand again contacts the pin contact 58. However, it is possible to provide additional hour hand pin contacts for operation more often than once every 24 hours if desired.

Therefore, it will obviously be seen that the time duration of the feeding operation by the feeder 22 will depend upon the length of the ribbon contact 52. This contact period can be varied to provide feed periods of varying duration; however, the normal feed period is 2½ minutes. It would be impossible to provide such a small feed period duration by relying solely upon the hour hand since the period of time that the hour hand will contact the pin is much greater to its more slower rate of movement and even if a short ribbon contact is used.

Additionally, the time period of a feeding operation can also be extended by the insertion of additional minute pins so that the minute hand contact can continue through one or more adjacent pins.

I claim:

1. An automatically operable control means for an alternating current drive motor of a feed dispensing means for actuating said motor at selected times for a given time of operation for dispensing feed during said period of operation, said control means comprising battery means, clock means connected to said battery means for operation, an hour hand and a minute hand on said clock means, ribbon contact members respectively extending from the ends of said hour hand and said minute hand, a first circular array of fixed socket members capable of fixedly supporting an hour hand contact pin engageable by the ribbon contact on the hour hand, a second circular array of fixed socket members capable of fixedly supporting a removable minute hand contact pin engageable by the ribbon contact on the minute hand, electrical conductor means connecting all of said socket members of said first circular array to each other, electrical connector means connecting all of said socket members of said second circular array to each other, inverter means having a first pole connected to one pole of said battery means and a second pole connected to the other pole of said battery means through a circuit including conductor means connecting a first normally open switch contact of a first relay solenoid and a second normally open switch contact of a second relay solenoid so that said first and second relay solenoids must be operated simultaneously to close said first and second normally open switch contacts to provide current to said inverter, power output lines from said inverter for providing alternating current to said alternating current motor upon operation of said inverter, the coil of said first solenoid being connected to said first circular array of fixed socket members so that engagement of the ribbon contact on the hour hand with a contact pin in the first circular array actuates said first solenoid, said second solenoid being connected to said second circular array of fixed socket members so that engagement of the ribbon contact on the end of the hour hand with a pin contact in said second circular array energizes said second solenoid whereby said inverter is operated to provide alternating current to the alternating current motor.

2. The invention of claim 1 wherein said socket members of said first circular array and of said second circular array comprises tubular members threaded on their interior with said contact pin having mating threads receivable into said tubular members.

3. The invention of claim 2 wherein said clock is an automobile-type clock that is intermittently wound by said battery.

4. The invention of claim 3 wherein said hour hand is removable to permit substitution of another hour hand having a ribbon contact of different length to vary the time period that the ribbon contact will be in contact with a particular pin.

5. The invention of claim 1 wherein said clock is an automobile-type clock that is intermittently wound by said battery.

bile-type clock that is intermittently wound by said battery.

6. The invention of claim 5 wherein said hour hand is removable to permit substitution of another hour hand having a ribbon contact of different length to vary the time period that the ribbon contact will be in contact with a particular pin.

7. The invention of claim 6 wherein said hour hand and said minute hand are connected by a common connector to said other pole of said battery means.

8. The invention of claim 7 additionally including a removable housing enclosing said clock face but removable for enabling access to said clock face.
